DESIGN FOR A TOY CLOWN

Gotthilf Lehmann, New York, N. Y.

Application January 17, 1947, Serial No. 136,198

Term of patent 14 years

(Cl. D34—15)

To all whom it may concern:

Be it known that, Gotthilf Lehmann, a citizen of the United States of America, resident of New York, in the county of Bronx and State of New York, has invented a new, original, and ornamental Design for Toy Clown, of which the following is a specification, reference being had to the accompanying drawing, forming part thereof.

Figure 1 is a front elevational view of the toy clown, showing my new design.

Figure 2 is a top plan view of the same.

Figure 3 is a front elevational view of the toy clown in another position.

Figure 4 is a side elevational view of the toy clown as shown in Figure 3.

I claim:

The ornamental design for a toy clown, as shown.

GOTTHILF LEHMAN.
